UNITED STATES PATENT OFFICE.

ISRAEL S. THOMPSON, OF ASHLAND, WISCONSIN.

DESIGN FOR A BREAD-BOARD.

SPECIFICATION forming part of Design No. 33,418, dated October 23, 1900.

Application filed October 1, 1900. Serial No. 31,723. Term of patent 7 years.

To all whom it may concern:

Be it known that I, ISRAEL S. THOMPSON, a citizen of the United States, and a resident of Ashland, in the county of Ashland and State of Wisconsin, have invented and produced a new and original Design for a Bread-Board, of which the following is a full, clear, and exact specification.

Reference is to be had to the accompanying drawings, forming a part of this specification, in which similar characters of reference indicate corresponding parts in both views.

Figure 1 is a perspective view of the bread-board, showing my design; and Fig. 2 is a transverse section of the same.

The design in its entirety consists of a board A, approximately rectangular in shape and surrounded at the ends and rear by a rim B, extending above the top and below the bottom of the board, the rim appearing or-

namented by a beading C and handles D, the end portions of the rim tapering, as is plainly shown in Fig. 2.

The leading feature of the design consists of the board, with the rim extending above the top of the board and below the bottom thereof.

Having thus described my invention, I claim as new and desire to secure by Letters Patent—

The design for a bread-board herein shown and described.

In testimony whereof I have signed my name to this specification in the presence of two subscribing witnesses.

ISRAEL S. THOMPSON.
